UNITED STATES PATENT OFFICE.

LOUIS GOHLKE, OF GRAND RAPIDS, MICHIGAN, ASSIGNOR TO T. STEWART WHITE, THOMAS FRIANT, GAIUS W. PERKINS, AND CHARLES J. REED, OF SAME PLACE.

DESIGN FOR A CARPET-SWEEPER CASING.

SPECIFICATION forming part of Design No. 24,591, dated August 20, 1895.

Application filed September 14, 1894. Serial No. 523,042. Term of patent 7 years.

To all whom it may concern:

Be it known that I, LOUIS GOHLKE, a citizen of the United States, residing at Grand Rapids, in the county of Kent and State of Michigan, have invented a certain new and original Design for Carpet-Sweeper Casings, of which the following is a specification.

This design relates to a carpet-sweeper casing, and the distinctive features thereof are the longitudinally rectilinear top of the case, having a central transversely curved or molded panel and two convex inclined panels at each side thereof, as more fully illustrated in the accompanying drawings, in which—

Figure 1 is a plan view of a carpet-sweeper casing embodying said design, and Fig. 2 an end elevation of the same.

Like letters refer to like parts in both of the figures.

A represents the central panel, having a convex middle portion and concave side portions and quarter-round edges.

B B represent intermediate side panels,

parallel to and at each side of the middle panel A, and having their adjacent edges beneath the same and inclined downward and outward at about twenty degrees, and having convex surfaces and quarter-round outer edges.

C C are outer panels, having their inner edges beneath the outer edges of the panels B B and inclined outward and downward therefrom at an angle of about fifty-five degrees, and having their outer edges quarter-round, all of said panels being longitudinally rectilinear, substantially as shown.

What I claim is—

The design for a carpet sweeper casing substantially as shown and described.

In testimony whereof I affix my signature in presence of two witnesses.

LOUIS GOHLKE.
